(57) **CLAIM**

The ornamental design for a collapsible audio/video stand, as shown and described.

DESCRIPTION

FIG. 1 is a perspective view of my new design;
FIG. 2 is a front elevational view thereof;
FIG. 3 is a rear elevational view thereof;
FIG. 4 is a top view thereof;
FIG. 5 is a bottom view thereof;
FIG. 6 is a right side view thereof, the left side being a mirror image;
FIG. 7 is a perspective view of a second embodiment of my design;
FIG. 8 is a front elevational view thereof;
FIG. 9 is a rear elevational view thereof;
FIG. 10 is a top view thereof;
FIG. 11 is a bottom view thereof; and,
FIG. 12 is a right side view thereof, the left side being a mirror image.
